UNITED STATES PATENT OFFICE.

ALFRED E. SHEPHERD, OF FLINT, AND EDWARD G. LOVERING, OF DETROIT,
MICHIGAN.

METHOD OF MANUFACTURING FILIGREE METAL LAMP SHADES.

Application filed March 11, 1922. Serial No. 542,897.

To all whom it may concern:

Be it known that we, ALFRED E. SHEPHERD and EDWARD G. LOVERING, citizens of the United States, residing at Flint, Genesee County, State of Michigan, and Detroit, county of Wayne, State of Michigan, respectively, have invented a certain new and useful Improvement in Methods of Manufacturing Filigree Metal Lamp Shades, and declare the following to be a full, clear, and exact description of the same, such as will enable others skilled in the art to which it pertains to make and use the same, reference being had to the accompanying drawings, which form a part of this specification.

Our invention relates to a method of manufacturing a filigree metal lamp shade by electrical deposition of metal over a non-metallic filigree backing as hereinafter described.

The object is to produce filigree metal lamp shades easily and cheaply in an infinite number of designs, and produce exactly the design desired.

A further object is to produce accurately in filigree metal a perforated paper or lace work design at a slight cost through the use of our process of electrical deposition.

These and other objects together with the details of working the process and construction of the article will more fully appear from the following description, appended claims and accompanying drawings, in which:

Figure 1 is a cross-sectional view through the treating tank.

Fig. 2 is a perspective showing the electrically deposited layer of metal partially stripped away at the bottom from its supporting plate.

Fig. 3 is a cross section through the metal plate which carries the filigree backing on which the metal is deposited.

Fig. 4 is an elevation of a simple design formed in filigree metal.

Fig. 5 is an elevation of a filigree metal candle shade.

Fig. 6 is a perspective of the frame work for the shade illustrated in Fig. 5.

Our invention comprises the construction of filigree metal lamp shades by electrical deposition of metal over a filigree backing the design of which it is desired to reproduce in the filigree metal work of the shade.

We prefer to use, because of the many

forms in which it may be obtained and its comparatively inexpensive character, a backing of filigree paper. These perforated paper sheets are obtainable in an infinite variety of designs. However, it is apparent that a backing of other material such as lace might be utilized. This perforated paper backing, because of its fragile character, must be suitably supported for the electrical deposit of the metal thereon, and we prefer to deposit the layer of metal thereon as a sheet and then strip it off and form it into the desired shape to make a shade, securing such strip or layer of metal over a suitable metal shade frame work.

Let 10 indicate the tank which contains a suitable electrolyte solution 11. The anode 12 is a metal bar from which the deposit is to be made, such as a bar of copper, and the lead-wire from the source of current supply 13 is itself indicated as 14. The lead-wire to the cathode is indicated as 15. At the cathode is our filigree backing, metal coated to receive a deposit, and suitable support. A suitable method which we have used is to spread a coating of wax 16 over a suitable metal plate 17, which plate is connected with the lead-wire 15. Our filigree paper backing 18 of whatever design it is desired to use is covered on one side with a suitable coating of metal 19 such as a bronze powder, plumbago, et cetera, which is then spread over the wax surface of the metal plate 17 which serves as the cathode. Sufficient wax is removed from the plate as at 20 to provide a metallic conductor through the plate between the metal coating 19 of the paper sheet and the metal base 17 of the plate so that the metallic connection with the bath will be complete.

The current is then permitted to pass through the tank for that period of time which is sufficient to deposit a layer of metal of the desired thickness at the cathode. The metal plate 17 is now removed from the bath and the deposited layer of metal 21 with its adhering portions of backing is stripped from the wax surface of the plate. We now have a sheet of filigree metal of the same design as the paper backing. It will be noted as shown in Fig. 3 that the deposited metal has formed around the edges of the perforated paper form so that when this layer of deposited metal is stripped from the wax surface of the plate, portions of the

paper form adheres thereto by virtue of the metal engaging over the edge thereof. These adhering portions of paper do not interfere with the use of this metal sheet for a lamp shade, as the side to which the paper adheres would be used as the inside of the shade; however, they may be removed if desired.

This may be used as it is as a metal lace or doily if desired. In connection with the manufacture of lamp shades, however, this metal sheet is shaped and formed over a suitable frame work 22 to which it is preferably secured by brazing or soldering to form a complete lamp shade. The metal filigree sheet may be cut if desired to aid in the shaping and then soldered to form an integral metal structure, and shades of varied and attractive designs are easily formed. These shades are generally used in connection with a silk lining which is secured thereto, though this forms no part of the invention.

What we claim is:

- 25 1. The art of making by electro-deposition in metal filigree a reproduction of a perforated paper sheet which consists in coating one surface of such sheet with a conducting medium, applying the opposite surface thereof to the waxed surface of a metal plate to be used as one terminal in an electro deposition bath so that the paper sheet will adhere to such waxed surface to be supported thereby, removing a portion of the wax to establish direct connection between the coated surface of the paper and the body of the plate, and electrically depositing metal on such metal coated surface of the paper sheet.
- 30 2. The art of making by electro-deposition in metal filigree a copy of a fragile non-metallic filigree which consists in covering one surface of the non-metallic filigree with

a conducting medium, providing a metal plate to be used at one terminal in the electro-deposit bath with a surface coating of adhesive material, spreading the non-metallic filigree over the adhesive surface of such metal plate so that the uncoated surface of the filigree adheres to the adhesive surface 50 of the plate to be supported thereby, providing an electric contact between the coating of the filigree and the metal plate and placing the plate carrying such filigree in an electro-deposit bath, and electrically depositing metal on the metal coated surface of such filigree.

3. The method of forming by electro-deposition in openwork sheet metal, an imitation of a fragile non-metallic filigree which consists in covering one surface of the non-metallic filigree with a conducting medium providing a support with an adhesive surface, spreading the uncoated surface of such filigree over the adhesive surface of the support to be carried thereby, establishing electrical connection between the coated surface of the filigree and a source of electric current, and electrically depositing metal on the metal coated surface of said filigree.

4. The process of forming by electro-deposition, a filigree metal duplicate of a fragile non-metallic filigree which consists in covering one surface of the non-metallic filigree with a conducting medium providing a support for the filigree with an adhesive surface, spreading the filigree over such adhesive surface for support thereby with the coated surface outside, disposing the filigree support in an electro-deposit bath, and electrically depositing metal on the coated surface of the filigree.

In testimony whereof we sign this specification.

ALFRED E. SHEPHERD.
EDWARD G. LOVERING.
